(57) **CLAIM**

The ornamental design for a front combination lamp for automobile, as shown and described.

DESCRIPTION

FIG. 1 is a front view of a front combination lamp for automobile;

FIG. 2 is a plan view of the front combination lamp for automobile;

FIG. 3 is a right side view of the front combination lamp for automobile;

FIG. 4 is a front perspective view of the front combination lamp for automobile, as seen from the right upper side; and,

FIG. 5 is a rear perspective view of the front combination lamp for automobile, as seen from the right lower side.

In the drawings, the broken lines form no part of the claimed design.
